UNITED STATES PATENT OFFICE.

GEORGE S. TURNER, OF GOWANDA, NEW YORK.

HAIR-DUSTER.

1,192,711.

Specification of Letters Patent. Patented July 25, 1916.

Application filed February 17, 1916. Serial No. 78,860.

To all whom it may concern:

Be it known that I, GEORGE S. TURNER, a citizen of the United States, residing at Gowanda, in the county of Cattaraugus and 5 State of New York, have invented certain new and useful Improvements in Hair-Dusters, of which the following is a specification.

The present invention relates to improvements in that class of brushes employed in 10 tonsorial parlors and known as hair dusters.

In carrying out my invention it is my purpose to produce a hair duster having a reservoir for containing the powder, to arrange a valve between the reservoir and an 15 opening in the brush head whereby powder may be fed from the reservoir to the brush at desired intervals and in desired quantities.

It is a further object of the invention to 20 provide a hair duster with a hollow handle which comprises a reservoir for the powder, to arrange the handle with a closure or cap, whereby access to the reservoir may be obtained, and to further arrange a spring 25 pressed slideable gate or valve between the reservoir and an opening in the head of the brush, and to provide the stem of the valve or gate with an operating handle disposed conveniently to the operator, whereby a desired 30 quantity of the powder may be fed from the reservoir to the brush.

It is a still further object of the invention to provide a powder reservoir, in the nature of a handle, which may be applied to hair 35 dusters of the ordinary construction, the said handle having a valve arranged in convenient position to be actuated by the operator whereby a desired amount of powder may be fed from the reservoir to the brush.

40 A still further object of the invention is to provide a valve carrying member which may be arranged upon the top or head of any ordinary brush, to form the head of the brush with an opening in a line with the 45 valve, and to provide a powder reservoir in the nature of a hollow handle which may be readily associated with the brush head to secure the valve carrying member thereon.

50 A further object of the invention is to provide a valve carrying member adapted to be arranged upon the top of any ordinary brush that is provided with an opening to communicate with the valve and to arrange a powder reservoir to surround the 55 valve carrying member and to be connected

with the head of the brush, and to provide means upon the said valve carrying member whereby the valve may be positively held in a normally closed position so that powder from the reservoir will be prevented from 60 passing through the valve opening except when the valve is actuated.

With the above and other objects in view, the improvement resides in the construction, combination and arrangement of parts set 65 forth in the following specification and falling within the scope of the appended claims.

In the drawing: Figure 1 is an elevation of a brush constructed in accordance with the present invention, the handle or reservoir of the same being in section, Fig. 2 is an enlarged horizontal sectional view approximately on the line 2—2 of Fig. 1, Fig. 3 is a vertical sectional view approximately on the line 3—3 of Fig. 2, Fig. 4 is a perspective view of the valve and stem therefor, and Fig. 5 is a perspective view of the plate having the spring members which 70 75 contact with the valve for holding the same tightly against its seat.

With the present construction of brushes used in tonsorial parlors for applying a powder to the neck and face of a person and which to the trade is known as a hair duster, the brush is inserted in a receptacle containing powder so that a desired amount of powder will be received between the hairs or bristles of a brush, and the brush or duster is then conveyed to the person upon which it is to be used and the powder applied. 80 85 90 With such a practice a large amount of powder is wasted and the method is unsanitary, for the reason that the brush is continuously used upon different persons and the same being constantly inserted in the powder permits of the ready conveying of diseased germs from one person to another.

With my device only a certain quantity of powder is fed from the reservoir to the brush and this powder can be used only upon 100 one person, as it is evident that all of the powder contained in the hairs or bristles of the brush may be removed therefrom by the simple operation of shaking the said brush. Also with my improvement it is not absolutely necessary that a brush of a particular construction be employed, although I have found it convenient to so illustrate the device in the accompanying drawing, as will be apparent when the details of construction 105 110

are more fully disclosed, that the valve carrying member may be applied to the heads of various designs of brushes.

In the drawing, the numeral 1 designates 5 the duster and 2 the head thereof. In the present instance the head is provided with peripheral threads and is centrally formed with a depending sleeve 3 that communicates with the hairs or bristles of the brush proper.

10 Arranged over the head 2 and resting thereon is a valve carrying member 4. This member is preferably in the nature of a block having a rounded periphery corresponding in size to that of the head of the 15 duster and the same is centrally formed with an opening 5 that communicates with the bore of the sleeve 3. The valve carrying member or block 4 is formed upon its upper face with a longitudinally extending substantially rectangular channel 6 which intersects the opening 5. The lower wall of the channel adjacent one of the sides of the opening 5 is formed with a lug 8, the said lug being provided with a depression or 20 opening which alines with a similar opening 9 provided in the wall between the periphery of the block 4 and one of the end walls of the channel 6, and arranged in these openings is the stem 9' of a flat valve 10. 25 The valve is, of course, disposed to close the opening 5 and the stem 9' is provided with an offset portion or collar 11 that is adapted to be contacted by one end of a helical spring 12, the said spring surrounding the stem 9' 30 and having its opposite end contacting with the lug 8 so as to normally slide the stem to cause the valve 10 to be disposed over the opening 5 in the block 4. The stem extends a suitable distance beyond the periphery of 35 the block and is provided with an operating head 13.

Arranged to close the channel 6 between the lug 8 and the portion thereof provided with the opening 9 is a flat spring plate 14, 40 the said plate being secured to the block 4 in any desired or preferred manner, and this plate has its inner end slotted to provide a central spring tongue 15 that exerts a tension against the stem 9 to force the 45 valve 19 upon the lower wall of the channel or the valve seat, so that the valve will positively close the opening 5. The said inner end of the plate to the opposite sides of the tongue 15 and between certain of the 50 slits is bent downwardly to provide right angular lips 16, and these lips are arranged to the opposite sides of the valve stem and engage with the lug 8 to close the opening 55 therein through which the valve stem passes, to serve as a guide for the valve stem as 60 well as a closure for the portion of the chamber within which the spring is arranged and prevent the powder from permeating through the said opening to within 65 the spring receiving chamber.

The block has its underface formed with a rectangular depression within which is pivoted a substantially rectangular bail or handle 17, and this bail may be swung outwardly of the block when the block is 70 handled.

The numeral 18 designates the hollow handle which provides the reservoir for the powder, and this handle has its lower end threaded, as at 19, to engage with the threaded periphery of the head 2 of the duster, the said handle being formed with an inturned portion or rim 20 that contacts with the upper face of the block to force the same firmly against the head of the brush. It is, of 75 course, to be understood that the threaded portion of the handle is provided with a suitable slot or opening through which is passed the stem of the valve, the upper and reduced end of the hollow handle, indicated 80 for distinction by the numeral 21, having a reduced mouth 22 which is formed with exterior threads, the said threads being engaged by a flange 23 upon a cap 24 and the said cap is provided with a ring 25 whereby 85 the duster may be suspended from a suitable support when not in use. The cap 24, of course, permits of access to the hollow handle or reservoir so that the powder may be supplied thereto when desired. 90

95 From the above description, taken in connection with the accompanying drawing, the simplicity of the device, as well as the advantages thereof will, it is thought, be perfectly apparent to those skilled in the art to 100 which such invention appertains without further detailed description.

Having thus described the invention, what I claim is:

1. In combination with a brush having its 105 head provided with an opening, and a hollow handle removably connected to said head, of a member resting upon the head and sustained thereon, said member having an opening registering with the opening of 110 the head having a transverse channel in its upper face which intersects the opening, a flat valve in the channel for normally closing the opening, a stem for the valve passing through the member and through one side 115 of the hollow handle, spring means co-acting with the stem for moving the valve to inoperative position, a protector plate bridging a portion of the channel and inclosing said spring means, and a spring element associated with said plate and co-acting with the valve to retain the latter seated. 120

2. In a device for the purpose set forth, the combination with a brush having its 125 head formed with a depending sleeve, and a hollow handle threadedly engaging with the sleeve, of a member arranged on the head and sustained thereon by contacting engagement with the handle, said member having an opening alining with the sleeve 130

and being further provided upon its upper face with a longitudinal channel, said member being provided with a lug in the channel adjacent the opening in the member, a flat 5 valve in the channel for closing the opening, a stem for the valve passing through the lug, the member and through the hollow handle, a collar on the stem, a spring upon the stem co-acting with the lug and with 10 said collar, a plate secured to the upper face of the member and bridging a portion of the channel to inclose a portion of the stem, the

spring and the lug, said plate having a spring tongue contacting with the stem of the valve, and depending lips upon the plate 15 disposed to the opposite sides of the stem and contacting with the lug to close the opening therein.

In testimony whereof I affix my signature in the presence of two witnesses.

GEORGE S. TURNER.
